UNITED STATES PATENT OFFICE.

JOSEPH H. AMIES, OF READING, PENNSYLVANIA.

UMBRELLA OR PARASOL.

SPECIFICATION forming part of Letters Patent No. 364,391, dated June 7, 1887.

Application filed February 23, 1886. Serial No. 192,860. (No model.)

To all whom it may concern:

Be it known that I, JOSEPH H. AMIES, a citizen of the United States, residing in Reading, Pennsylvania, have invented certain Improvements in Umbrellas and Parasols, of which the following is a specification.

My invention relates to that class of umbrellas in which the cover is detachable from the frame, the objects of my invention being to provide for the proper confinement of the cover irrespective of slight differences in the sizes of different covers, to make a neat finish at the upper end of the umbrella or parasol, and to provide the cover with retaining-clips, which can be readily applied to or removed from the tip ends of the ribs.

In the accompanying drawings, Figure 1 is a sectional view, partly in elevation, of sufficient of the upper portion of an umbrella or parasol to illustrate my invention; Fig. 2, a sectional plan on the line 1 2, Fig. 1; Fig. 3, perspective views of the parts comprising the device for attaching the cover of the umbrella. Figs. 4 and 5, views showing the device for connecting the cover to the tip ends of the ribs; and Fig. 6, a perspective view of the notch which carries the ribs, the parts comprising the notch being detached from each other, and part of two of the ribs being also shown.

A represents part of the stick of an umbrella or parasol, and B the notch, to which are hung the ribs D, this notch and the ribs being constructed in the peculiar manner described hereinafter.

Secured to the stick, above the notch B, is a ferrule, F, threaded exteriorly for the reception of an internally-threaded sleeve, G, the lower portion of which has a recess, a, for the reception of the upper portion of the cover J of the umbrella or parasol. This cover has the usual central opening for the passage of the stick and ferrule F, which opening is preferably surrounded by a strengthening cord or wire, and the cover is provided around its outer edge with clips M, whereby it is retained by the tip ends of the ribs D.

Owing to the provision of the recess a in the confining-sleeve G, the upper end of the cover can be secured to the ferrule by a con-

fining cord or band at any distance above the lower end of said ferrule which may be demanded by the size of the cover, the proper confinement of the cover to the frame being effected by screwing down the sleeve G, the lower end of which bears upon the cover and depresses the same to its proper position at and near the ribs.

If desired, the cover may be confined between the lower edge of the sleeve G and a nut, b, adapted to the threaded exterior of the ferrule F and adjustable thereon, so as to properly confine the cover, whatever may be the position assumed by the retaining-sleeve G.

The ferrule F, with its retaining-sleeve, forms an attachment which can be readily applied to the stick of an ordinary umbrella or parasol, the upper portion of the sleeve fitting snugly to the ferrule above the threaded portion of the latter and covering the thread, so that the latter does not detract from the general neat appearance of the attachment.

In order to permit the removal of any one of the ribs when it becomes broken or otherwise defective, I provide each rib at the upper end with laterally-projecting pivots f, preferably formed by the same dies that are used for flattening the upper end of each rib.

The notch B has radial slots g for the reception of the reduced portions of the ribs, the pivot-heads being confined to the notch by a nut, h, adapted to the threaded stem of the notch.

In order to permit the insertion or removal of a rib, it is necessary to remove the nut, so that the pivot-head of the rib can be withdrawn from the notch or the pivot-head of a new rib inserted.

The stretchers should be connected to the runner in the same manner, so that both the rib and stretcher can be removed in the event of an accident to either.

The clips M, with which the outer end of the cover is furnished, are preferably made of wire, sheet-metal plate, or other suitable material, and are of the shape shown in Fig. 5, so as to provide an eye, m, contracted at the lower end, and an inner eye, n, whereby the secure attachment of the clip to the umbrella by sewing or otherwise is effected, the en-

larged portion of the outer eye being intended for the passage of the knob *p* on the tip of the rib, and the contracted portion of said eye receiving the reduced portion of the rib at the 5 base of the tip, as shown in Fig. 4, when the cover is properly applied to the ribs.

The cover preferably projects beyond the clip, as shown in Fig. 4, so as to hide said clip.

I claim as my invention—

- 10 1. The combination of the umbrella-stick, the notch and the ribs hung thereto, the cover having around the lower edge clips for adaptation to the lower ends of the ribs, and a cover-retainer consisting of a ferrule, *F*, secured to the stick above the notch, and a sleeve, *G*, adjustable on said ferrule, the cover being secured to the ferrule above the lower end of the same, and the sleeve bearing upon the upper side of the cover and having an internal
- 15

rcess, so as to permit the attachment of the 20 cover to the ferrule at a point above the lower end of the sleeve, all substantially as specified.

2. The combination of the ribs, each having a flattened portion at the base of the tip, with the cover having clips, each with an eye enlarged at the inner portion for the passage of the tip and contracted at the outer portion for the reception of the flattened portion of the rib at the base of the tip, all substantially as specified. 25

In testimony whereof I have signed my name to this specification in the presence of two subscribing witnesses. 30

JOS. H. AMIES.
